UNITED STATES PATENT OFFICE.

JOHANNES CRONING, OF HAMBURG, GERMANY.

MORTISE LOCK.

Application filed July 26, 1920. Serial No. 399,188.

(GRANTED UNDER THE PROVISIONS OF THE ACT OF MARCH 3, 1921, 41 STAT. L., 1313.)

To all whom it may concern:

Be it known that I, JOHANNES CRONING, a subject of the German Republic, and resident of Hamburg, Germany, have invented 55
5 certain new and useful Improvements in or Relating to Mortise Locks (for which applications for patent have been filed in Germany, March 22, 1919, Patent No. 337,487; in Holland, June 30, 1920, Patent No. 10 15,355; in Belgium, July 10, 1920, Patent No. 289,217; in England, July 8th, 1920, Patent No. 147,493; in France, July 8th, 1920, Patent No. 519,474; and in Switzerland, June 28th, 1920, Patent No. 89,518), 15 of which the following is a specification.

Cylindrical locks which can be adjusted to fit doors of different thickness are known, but the encasing portion of the lock is in the form of a rectangular box and houses the 20 cylindrical portion of the lock, which is secured by escutcheons. The operation of mortising the door frame for the box shaped member of the lock entails troublesome chisel work and the escutcheons of the lock 25 cylinder are a frequent source of error, especially when they are made two-sided so as to act for two lock cylinders at the same time.

The removal of these drawbacks is the 30 object of the present invention. The lock consists solely of two properly shaped interconnected cylinders of which the one lying transversely to the plane of the door is arranged in such a way that it can be 35 fastened to a flanged guard cylinder prior to being inserted in the door, and is then screwed into a similar guard cylinder fixed on the opposite side of the door, and secured in position by the cylindrical tube which 40 lies in the plane of the door. In this way the lock and casing cylinder are securely prevented from being unintentionally loosened. Moreover, the troublesome labour of chiseling out a mortise, as is necessary 45 in the case of box-shaped mortise locks, is overcome by boring a couple of holes.

The subject of the invention is illustrated in the drawing.

Figure 1 shows a vertical section of one 50 method of carrying out the invention.

Figure 2 is a section A—B of Figure 1.

Figure 3 is a modification and

Figure 4 the section C—D of Figure 3.

The door 1 is bored through horizontally

and carries on the one side—preferably the 55 inner—the threaded flange 2, which is provided with noses, wedges or pins 3 to prevent it from turning. The threaded flange 6, which is fixed to the cylindrical case 4 by the set screw 5, is inserted from the opposite side of the door and screwed on to the flange 2. The cylindrical casing 4 consists of the strengthened central portion 7 and the threaded members 8 and 9 on either side. The tumblers cylinders and their accessories 60 for operating the bolt are housed in the flanges 2 and 6, while the central portion 7 of the lock case 4 serves to house the mechanism transmitting movement to the bolt. These and the tumbler cylinders are omitted 65 in the drawing. The set screw 5 provided in the flange 6 protrudes into the slot 10 of the threaded socket 9, so that the flange 6 can be screwed on to the casing 4, to a greater or smaller extent, in accordance with the 70 thickness of the door, so as to hold it in the desired position, prior to being inserted in the door. The casing 4 is secured by the tube 11, introduced from the edge of the door, said tube screwing into the casing 4 75 and serving as a guide for the bolt.

In the form shown in Figures 1 and 2, the flanges 2 and 6 are provided with internal threads, and the cam pivot 12 for operating the bolt is eccentric in relation to the central 80 point of the casing 4.

In the modification shown in Figures 3 and 4, the flanges 2 and 6 are provided with outside threads and the cam pivot 12 is concentric with the casing cylinder 4, the central portion 7 of the lock case 4 differing accordingly.

Other modifications are also possible, nevertheless, the essential feature of the invention consists in that the casing with which the adjustable circular flanges are connected is cylindrical or approximately cylindrical, so that it can turn in the hole bored through the door, and that this rotation is prevented, when the casing has been inserted, by a tubular screw connection which is introduced from the edge of the door and preferably serves as a guide for the bolt, this fastening device operating to best advantage in the central plane of the locking casing. Another essential feature of the invention is that the flanges are prevented from turning round by providing the 95 100 105

fixed flange with noses, wedges or pins which embed in the body of the door, whilst the other flange, prior to the insertion of the casing, is secured to the latter in accordance with the thickness of the door.

The bolt may be replaced by a latch.

What I claim is:

1. A mortise lock consisting of a cylindrical lock casing having pockets and threaded ends, screw flanges engaging said threaded ends for compensating for different door thickness, said flanges closing said pockets, a cylindrical bolt tube of smaller diameter than said casing and screwed there-to at right angles, and means to secure one of the flanges in adjusted position.
2. In a mortise lock, a cylindrical lock casing having tumbler receiving pockets and threaded ends and a middle compartment for the reception of bolt retracting mechanism, threaded flanges engaging the door
- 10
- 15
- 20

face and the threaded ends of said casing, one of said flanges having pins or lugs on its door contacting face, and the other flange having means to secure it against rotation with respect to said casing, said flanges closing the tumbler receiving pockets in the ends of said casing.

3. In a mortise lock, a cylindrical lock casing having tumbler receiving pockets and threaded ends and a compartment intermediate its ends for the reception of bolt actuating means, threaded flanges for engaging the ends of said casing and closing tumbler cylinder receiving pockets between said compartment and flanges, and a bolt receiving tube at right angles to said casing and in threaded engagement therewith.

Signed by me at Hamburg this 1 (first) day of July, 1920.

JOHANNES CRONING.
